[57] ABSTRACT

A hydraulic or air operated drill press. This device is composed primarily of hydraulic or air operated cylinder which provides pressure for a diamond core bit for drilling underwater holes.

3 Claims, 2 Drawing Figures

PATENTED MAR 27 1973

FIG. I

INVENTOR,
MARK C. ROGERS

RAM OPERATED DIAMOND CORE DRILL PRESS

SUMMARY

This invention relates to drill presses, and more particularly to a hydraulic or air operated diamond core drill press.

It is therefore the primary purpose of this invention to provide a drill press which will be power operated so as to expedite drilling operations as referring to underwater holes.

Another object of this invention is to provide a drill press which will have guide means within the base member so as to prevent wobbling of the bit when it is rotated.

Another object of this invention is to provide a drilling press of the type described which will have rack means which will aid in guiding the ram portion.

A further object of this invention is to provide an apparatus of the type described which will have a water swivel which will serve to cool the diamonds and wash away the cut concrete and the base member of the apparatus will include bolt fastening means for securing the apparatus to the concrete anchor.

A still further object of this invention is to provide an apparatus for drilling which might inherent properties, will increase the endurance of the diamond bit being used as well as expediting a drill operation.

Other objects of the present invention are to provide a ram operated diamond core drill press which is simple in design, inexpensive to manufacture, rugged in construction, easy to use and efficient in operation.

These and other objects will be readily evident upon a study of the following specification and accompanying drawing wherein:

FIG. 1 is a side view of the present invention; and

FIG. 2 is an enlarged view taken along the line 2—2 of FIG. 1.

DETAILED DESCRIPTION

According to this invention, a ram operated diamond core drill press 10 is shown to include a base member 11 from which is sufficiently secured and extending upwards a vertical rack 12 having a plurality of teeth 13 which provides guide means and mechanical elevation means for drilling portion of the apparatus. A bar 14 is fixedly secured in a horizontal position to the upper extremity of rack 12 and has vertically fixed thereto a ram cylinder 15 which may be air or hydraulically operated. Fixedly secured to base 11 of apparatus 10 is a support frame 16 of L-shaped cross sectional configuration, the opposite end being fixedly secured to the upper extremity of rack 12 and end bar 14.

A cross bar 17 provides further rigidity for frame 16 by being secured fixedly between support frame 16 at one end and fixedly secured at its other end in a suitable manner to rack 12. An air or hydraulic motor 18 includes lines 18' for feeding fluid or air thereto. Thus this motor is fluid-actuated. Attached to apparatus 10 is a free position control valve 19 having forward, neutral and reverse positions (not shown). Also carried by apparatus 10 is a regulator 19' for the purpose of applying a desired pressure to the ram cylinder 15 and its associated components. A water swivel 20' mounted on motor 18 provides a means of cooling its attached diamond bit 20" when apparatus 10 is in operation.

The lower extremity of bit 20" is guided within guide member 21 on the forward end of base 11. The bit 20" is further guided by guide member 22 carried slidably upon rack 12 and handles 23 serve to raise or lower the bit 20" manually and further aids drilling when prime hydraulic or air pressure is supplied to ram cylinder 15. Base member 11 includes a plurality of spaced apart bolt fasteners 24 for securing apparatus 10 to a concrete anchor so that the apparatus 10 will be fastened rigidly in order to effectively drill an opening.

In use, pressure is applied to the bit 20" by means of the hydraulic or air operated ram cylinder 15 which causes the bit 20" to cut more effectively than if it were manually operated when the pressure is controlled by means of regulator 19'. During drilling operations, the ram cylinder 15 applies downward pressure to the bit 20". However, more or less downward pressure may be regulated by turning the handles 23, depending upon the degree of hardness of the concrete being drilled.

The guide member 21 serves to effectively maintain the alignment of bit 20" by acting as barriers thereon prior to imparting vertical stability against wobbling when apparatus 10 is used for drilling operations. As shown in FIG. 1, shaft 25 on handles 23 has a pinion 26 meshing with teeth 13 on rack 12, whereby motor 18 may be raised or lowered. This shaft is supported in a bracket connected to the motor.

What I now claim is:

1. A ram operated diamond core drill press comprising a base member adapted to be fastened to a concrete anchor, a support frame secured to the base member to extend thereabove, a vertical rack fixed to the base member and support frame, a fluid-actuated motor supported on the rack for up and down movement, the motor having control valve means therefor, a diamond core drill connected to the motor to be turned thereby, a guide member disposed on the base for guiding the lower extremity of the bit during drilling operations, a water swivel mounted on the motor for supplying water for cooling the bit and removing cut particles of concrete, a ram cylinder attached to the support frame and being connected to the motor, the ram cylinder being operable for forcing the bit downwardly in order to expedite boring a hole in the concrete, the support frame being secured at one end to the base member and secured at its other end to the upper extremity of the rack, the rack being spaced from the support frame, and a cross bar securing the rack to the support frame for providing rigidity to the drill press.

2. The combination according to claim 1, wherein the base member includes a plurality of spaced T-shaped bolt fasteners, which provide means for securing the base member to the concrete anchor in order to render the drill press stationary and rigid while drilling, and a horizontal bar secured fixedly to the upper extremity of the rack and to the ram cylinder to rigidly support the latter, and a guide member secured to the motor and slidably engaging with the rack for guiding the motor for up and down movement.

3. The combination according to claim 1, wherein a regulator provides a means for imparting the desired force to the bit by the ram cylinder by regulating the fluid pressure thereon, the control valve provides a means for engaging and disengaging the motor, and a drilling operation is further aided by means of a rotat-

ble handle which is provided with a shaft having a pinion meshing with teeth of the rack, this shaft being supported in a bracket connected to the motor, thus enabling the operator to manually lower or raise the bit when desired.
